UNITED STATES PATENT OFFICE.

JAMES W. DWYER, OF ST. LOUIS, MISSOURI.

DESIGN FOR A COOKING-STOVE.

SPECIFICATION forming part of Design No. 16,931, dated October 12, 1886.

Application filed June 14, 1886. Serial No. 205,148. Term of patent 7 years.

To all whom it may concern:

Be it known that I, JAMES W. DWYER, of the city of St. Louis, Missouri, have invented and produced a new and original Design for 5 Cooking-Stoves, of which the following is a specification, reference being had to the annexed drawing, forming part thereof, and exhibiting the newly-designed stove in perspective.

10 The most pronounced feature of this design is the contrasted smooth and rough surfaces of the stove, the top A and the hearth B, as well as minor parts C, being smooth, and the upright surfaces D being roughened, as shown.

15 An additional feature is the vertical stripe E upon the roughened doors F G, consisting of the ribs e and the flowers e'. The legs F', roughened at f, smooth at f', and striped at f'', substantially as shown, are an adscititious 20 element of the design; and upon the oven-door is the shield G', and upon the door H at the front of the stove is the ornament h. The

oven-hearth I has a smooth margin, i, and a roughened depressed center, i'.

In its general outline the stove is cubical, its 25 top A projecting well from its sides, and the hearth B projecting markedly from its front.

I claim—

1. The design for a cooking-stove herein shown and described, the same consisting of 30 the smooth and rough surfaces in contrast, the roughened doors bearing the stripe E, the legs F, roughened at f, smooth at f', and striped at f'', the shield G', and the hearth having the smooth margin and roughened depressed center.

2. In a design for a cooking-stove, the legs F, roughened at f, smooth at f', and striped at f'', as herein shown and described.

JAMES W. DWYER.
